UNITED STATES PATENT OFFICE.

WILLIAM WALLACE KEMP AND WILLIAM H. VAN HORN, OF BALTIMORE, MARYLAND.

FLUID-MIXING APPARATUS.

1,141,466.

Specification of Letters Patent. Patented June 1, 1915.

Application filed August 13, 1913. Serial No. 784,652.

To all whom it may concern:

Be it known that we, WILLIAM W. KEMP and WILLIAM H. VAN HORN, citizens of the United States, residing at Baltimore, in the 5 State of Maryland, have invented new and useful Improvements in Fluid-Mixing Apparatus, of which the following is a specification.

This invention relates to a fluid mixing and 10 distributing system, and has for its object to provide an apparatus by means of which fluids either gaseous or liquid may be mixed in exact and proper proportions, which proportions may be changed at the will of the 15 operator without interruption to service, the apparatus continuing to mix the fluids with exactness at the proportions for which it is set until changed.

This apparatus while adapted for both 20 liquid and gaseous fluids as stated, is illustrated and described as arranged for mixing manufactured or natural gas with air whereby a product is obtained that will burn with perfect combustion; give increased 25 efficiency of service; reduce the consumption of gas, and by the use of which Bunsen burners may be dispensed with and the fire at the point of consumption of the mixture be controlled by a single valve.

30 In the drawings is illustrated an embodiment of the invention designed for mixing two fluids only, but it will readily be apparent that the invention may be extended to mix more than two fluids when so desired, such changes being made with slight alteration of the apparatus and without departing from the spirit of the invention.

In the drawings, Figure 1 is a plan view 40 of the complete apparatus in a somewhat diagrammatic form. Fig. 2 is an end elevation of the fluid measuring mechanism. Fig. 3 is a side elevation of the same. Fig. 4 is an end view illustrating a modified form of the measuring mechanism. Fig. 5 is a 45 sectional view illustrating a gas regulator and relief valve operated by said regulator. Fig. 6 is a detail view of the relief valve. Fig. 7 is a diagrammatic view illustrating the lay-out of the cams for operating the 50 fluid measuring mechanism. Figs. 8 and 9 are diagrammatic views illustrating electrical devices for operating the measuring mechanism. Fig. 10 is a plan view of the measuring mechanism operated by a metering wheel. Fig. 11 is an end view of the 55 same. Fig. 12 is a view illustrating a modified

specification of the cams which may be employed with either form of the apparatus. Fig. 13 is a diagrammatic view illustrating the layout of the cams as arranged for the metering 60 wheel. Fig. 14 is a view similar to Fig. 1 for a duplex supply of gas.

Referring to the drawings wherein like reference characters are used to indicate the same parts in the several figures, 10 indicates an inlet pipe for a fluid which in the type of the machine illustrated is gas, either manufactured gas from the city mains, or other place of production, or natural gas from a gas well or other suitable source of supply. The gas is led by the pipe 10 into a reservoir 11 of a size to contain a sufficient volume of gas from which to draw the supply for delivery to the mixing mechanism. Within the reservoir 11 is a pump, blower or 75 other compressor 12 from which a pipe 13 leads to a cut-off valve 14 through which a determined quantity of the gas passes when opened into a pipe 15 forming one leg of a Y 16, and from thence to a mixing receptacle, here shown as a pipe 17, into a storage tank 18 from whence it is delivered through suitable pipes to be consumed. When natural gas is to be mixed the reservoir 11 and compressor 12 may be found unnecessary as 80 the pressure of the gas will be sufficient. The compressor 12 is driven by an electric motor 19 or other power connected to a rotatable shaft 20 to one end of which is connected the compressor 12. The other end 85 of the shaft 20 drives a pump or compressor 21 which in the present instance is used to compress and drive air through a pipe 22 to a valve 23 similar to the cut-off valve 14 from which valve 23 the air passes by way 95 of a pipe 24, forming the other leg of the Y 16, into the common mixing pipe 17.

The cut-off valves 14 and 23 are not confined to any particular type of valve, but may vary to suit circumstances. In the 100 present instance ordinary lift valves are employed the stems 25, 25^a of which project downwardly through stuffing glands in the underside of the casings. The valves 14 and 23 are spaced a predetermined distance 105 apart and are each secured to a bracket 26 bolted firmly to a stationary frame 27 provided with bearings for a horizontal sliding rod 28 and a shaft 29, on which latter are mounted cams 30, 30^a. Mounted to rock 110 freely on the sliding rod 28 are two bell-crank levers 31, 31^a, which are held apart a

distance equal to the distance between the centers of the valves 14 and 23 by collars 32 fixed on said rod on each side of said levers. The depending arms 33, 33^a of the bell-crank 5 levers are each provided with a roller 34, 34^a, that bear upon the respective cams 30, 30^a. The horizontal arms 35, 35^a extend outwardly beneath the respective valve stems 25, 25^a, and are each provided with a 10 finger 36, 36^a which lies parallel to the sliding rod 28, and is of such length that in whatever position the rod may be placed the fingers 36, 36^a will be in position to engage the valve stems. 15 The cam 30 is provided with a number of elevations or lifts that lie side by side transversely, any one of which is adapted to rock the elbow lever 31 when the latter is moved into position in line therewith by 20 means of the sliding rod 28. These projections or lifts, indicated by the letters *a* to *h* inclusive, are of different lengths increasing by predetermined steps from the lift *a*, which is the shortest, to the lift *h*, the longest. 25 The ends *x* of all of the projections or lifts approaching the elbow lever 31 are in a line parallel to the axis of the cam 30, so that opposite whatever projection the elbow lever may be placed, the time of opening of 30 the valve 14 will be the same, the time of closing the valve however will vary according to the length of the projection or lift, and the quantity of gas passing through the valve will be proportional to the length of 35 time the valve is held open. The cam 30^a is likewise provided with projections or lifts *a'* to *h'* and similarly arranged thereon. Where a greater proportion of air than gas is needed, these lifts are longer than those 40 of the cam 30. Obviously, these conditions may be reversed or the conditions may require that the lifts be of the same length on both cams. The approaching ends *z* of the 45 projections or lifts *a'* to *h'* do not lie in a straight line as the similar ends *x* of the projections *a* to *h*, but are stepped back as shown in Figs. 2 and 7 a distance equal to the additional length of corresponding projections *a* to *h*. The annular distance between the ends *w* of the projections *a* to *h* and the ends *z* of the projections *a'* to *h'* is such that the instant the roller 34 of the lever 31 falls from any one of the projections *a* to *h* to close the gas valve, the corresponding projection of the group of projections *a'* to *h'* will act on the roller 34^a of the lever 31^a to open the air valve, and will hold said air valve open until the rear end *y* of said projection passes the roller 34^a, whereupon the air valve will close, and the gas valve again open instantly because the end *w* of the projections will be in position to lift the roller 34. The lifting ends *z* of the projections *a'* to *h'* are so spaced in sequence 60 of operation from the rear ends of the pro-

jections *a* to *h* that the instant the gas valve closes, the air valve will be opened, irrespective of the projections or lifts which may be acting on the levers.

The lengths of the projections or lifts *a* to *h* of the cam 30 and the corresponding projections *a'* to *h'* on the cam 30^a bear certain definite elective proportions one to the other for the purpose of holding the gas and air valves open definite periods of time to cut off varying proportions of gas and air that pass to the storage tank 18. The intermediate projections bear different ratios one to the other which may be arranged as desired for the purpose of obtaining a mixture substantially constant however rich or thin the manufactured or natural gas may be.

For the purpose of locking the elbow levers 31, 31^a, opposite corresponding projections or lifts on the cams 30, 30^a, the sliding rod 28 is provided with a series of perforations 37 equal in number to the number of projections on said cams and spaced apart the same distance as said projections. A pin 38 slidable in a bracket 39 bolted to the frame 27 is in position to enter one or the other of said notches after the rod has been moved to adjust the elbow levers and hold said rod against movement.

For the purpose of moving the cams 30, 30^a, any suitable means may be provided, in the present instance where the cams are shown as rotating a belt 40 connects a pulley 41 on the motor shaft 20 with a pulley 42 on the shaft 29 of said cams. The pulleys 41 and 42 are so proportioned as to drive the cams at the desired speed.

For the purpose of maintaining constant pressure at the cut-off valves 14 and 23, a pressure regulator is applied to the pipes which lead from the compressors to said valves. The compressor used on the gas pipe 13 is illustrated in detail in Fig. 5, and as there shown, a short pipe 43 connects the gas compressor 12 within the reservoir 11 with one end of a horizontal trunk 44 extending through the wall of said reservoir to the outside thereof. The other end of said trunk is connected by an upturned branch 45 to the bottom of a well 46. Within said well is an open cylinder 47 spaced from the wall thereof, which space contains a quantity of fluid 48, preferably mercury. A bell 49 has its open end immersed in the mercury or other fluid and is adapted to rise and fall as the pressure of the gas varies. A stem 50 attached to the bell 49 is guided at its upper end in the cap piece of the well 46, the lower end of said stem being attached to a crank 51 on one end of a rock shaft 52 that extends horizontally through the trunk 44 and carries at its opposite end within the reservoir 11 a relief valve 53 adapted to open and close ports

54 as the bell rises and falls to permit the gas, when the pressure increases, escaping back into the reservoir, and thus maintain an equal pressure at the cut-off valve 14. A pressure regulator 55 is connected to the air pipe 22. Said regulator may be the same as that described, or any other preferred form and controls a relief valve 56 similar to the valve 53, illustrated in detail in Fig. 6. In the operation of the machine as described, the shaft 20 is rotated by the electric motor 19, or other source of power to drive the compressors 12 and 21, said compressors forcing gas and air through the respective pipes 13 and 22 to the gas and air valves 14 and 23. The cams 30, 30^a being rotated at the same time by the belt 40 actuate the elbow levers 31, 31^a, to cause said measuring valves to open and close, the proportion of gas and air which pass through the valves being regulated by moving the sliding rod 28 to cause said elbow levers to be actuated by the proper projections on said cams 30, 30^a. The positions which said elbow levers assume with relation to said projections is to be determined by the degree of richness of the gas and desired quality. The richer the gas sooner will the gas valve be closed, while the air valve remains open a longer period. The several measured quantities of gas and air passing from the valves through the Y 16 into the pipe 17, become thoroughly mixed in the storage tank 18 from which it passes by pipe 57 through a check valve 58 and back fire preventer 59, to the several points of consumption. This storage tank and back fire preventer are shown located entirely outside the building containing the mixing apparatus. If from any cause the pressure of gas in the pipe 13 increases above a predetermined point the bell 49 of the pressure regulator will be lifted and the opening 54 of relief valve 53 increased, permitting sufficient quantity of gas to escape from the pipe 13 to practically maintain the desired pressure in pipe 13. The escaping gas passes into the reservoir 11 where it again passes through the compressor 12, and so no loss is sustained. In the same manner excessive air pressure escapes through the relief valve 56 into the atmosphere, there being no need of course of a reservoir for air.

5 A modification of the cut-off valve operating means is shown in Fig. 4. In this form of the apparatus the cams 30, 30^a act directly upon the valve stems 25, 25^a thus dispensing with the elbow levers 31, 31^a. The cams themselves in this arrangement may move longitudinally on the shaft 20, or the said cams may be fixed to the shaft and the shaft itself be made to move longitudinally in its bearings.

6 Whenever it is found necessary or de-

sirable to open and close the measuring valves 14 and 23 by devices at a distance therefrom this may be done very readily by means of a simple electrical device illustrated in Figs. 8 and 9. As shown in Fig. 75 8 the valve stems 25, 25^a, pass through the tops of the valves and through solenoid magnets 60, 60^a, which, upon closing the circuits therethrough draw up the valve stems, which, in this instance, are made of iron or 75 have their upper ends made of iron, and open the valves. The cams 30, 30^a, in this instance actuate levers 61, 61^a to close contacts 62, 62^a through suitable circuits that include solenoids 60, 60^a. In Fig. 9, instead 80 of cams 30, 30^a, commutators 63, 63^a, are provided that close circuits through brushes 64, 64^a, in circuit with the solenoids 60, 60^a, in the well-known manner.

It may at times be found desirable to use 85 in connection with the apparatus, a metering wheel for the purpose of driving the cams, and when such is the case the arrangement shown in Figs. 10 and 11 may be employed. In these figures, 65 indicates the 90 metering wheel mounted on a shaft 66 to which are also secured cams 30^b and 30^c on which are arranged several series of projections or lifts *a* to *h* and *a'* to *h'* respectively, similar to the projections shown and 95 described in connection with the cams 30, 30^a. In this instance, however, three or more series of lifts are preferably used on each cam due to the fact that the rotation 100 of the shaft 66 is quite slow and it has been found desirable to operate the cut-off valves 14 and 23 oftener than once in each revolution of the metering wheel. The projections or lifts *a* to *h* and *a'* to *h'* of the cams 30^b, 30^c 105 actuate elbow levers 31, 31^a to successively open the valves 14 and 23, as in the preferred form, to permit gas and air forced through the pipes 13 and 22 to pass for determined periods of time through said valves. The measured gas and air pass from the valves by pipes 67, 68, forming the legs of a Y 69 thence through a pipe 70 to the metering wheel 65 and from said metering wheel by a pipe 71 to a storage tank 18. 110

Air and gas under pressure from compressors admitted periodically in desired proportions to the mixing pipe 70 pass through said pipe to the metering wheel 65, rotating said wheel and the cams 30^b, 30^c, by means of which the cut-off valves are operated. From the metering wheel the mixed air and gas pass through the pipe 71 to the storage tank. 115

Instead of providing the cams 30 with a series of projections *a* to *h* with step-like rear ends *w*, as in the preferred form, said rear ends may be a straight line inclined to the axis of the drum as at *w'*, Fig. 12. In a similar manner the forward edge *z* of the projections *a'* to *h'* may be replaced by an 120 125 130

- inclined straight edge z' , Fig. 12. With lifts of the modified type the adjustments of the elbow levers 31, 31^a, thereto are practically indefinite instead of being limited to 5 the number of projections or lifts on the cams. The levers may be moved at will a very slight distance, the full width of the lifts or any fraction thereof in order to get the exact mixture desired.
- 10 In Fig. 13, the lay-out of the cams 30^b, 30^c, used with the metering wheel is shown in proper relation one to the other.
- A mixing apparatus such as described is 15 equally well adapted for intimately mixing all kinds of fluids, whether liquid or gaseous in correct proportions, which may be changed as desired by the simple operation of moving the sliding rod 28 to carry the elbow levers 31, 31^a, into position opposite 20 the proper pair of projections on the cams. As soon as this change has been made the apparatus continues its operation, measuring the fluids and mixing them in the proportions desired.
- 25 In Fig. 14 of the drawings, an installation is shown wherein there is associated with the cams 30, 30^a, a duplicate inlet pipe 10^a, a duplicate storage tank 11^a, containing a compressor 12^a, connections 13^a, 43^a, 44^a, 46^a, 30 and 53^a, to an additional gas cut-off valve 14^a and duplicate pipe communications 22^b from the air pump to an additional air cut-off valve 23^a which gas and air valves arranged for coöperation are fastened to brackets 26^a secured to a frame 27^a. There is a duplicate sliding rod 28^a provided with perforations to receive locking pin 38^a, and also duplicate devices (not shown in Fig. 14) for coaction with the 35 cams 30, 30^a for moving the valve stems. The said additional gas and air valves and connections are arranged as shown in Fig. 14 opposite the similar elements shown in Fig. 1, so as to be operated by the same 40 cams. Obviously by manipulation of the sliding rod 28^a these additional cut-off valves 14^a, 23^a may be operated to supply a different quality of gaseous mixture from that which is supplied by the cut-off valves 45 14 and 23, so that with the one installation or apparatus, fuel of different qualities may be supplied as is often desired for different purposes of utility in the same establishment.
- 50 55 What we claim is:
1. In a fluid mixing apparatus, the combination with a mixing receptacle, and means for compelling a plurality of fluids under pressure to be delivered separately thereinto, of a plurality of devices each adapted to interrupt the flow of one of said fluids, a plurality of mechanisms each for periodically operating one of such devices, and means for changing the relative periods 60 of operation of said mechanisms.

2. In a fluid mixing apparatus, the combination with a mixing receptacle, and means for compelling a plurality of fluids under pressure to be delivered separately thereinto, of a plurality of devices interrupting the flow of said fluids for controlling the proportionate quantities delivered, means for periodically operating such devices, and means for changing the relative periods of such operations. 7

3. In a fluid mixing apparatus, the combination with a mixing receptacle, means for compelling a plurality of fluids under pressure to be delivered separately thereinto, of a plurality of devices for interrupting the flow of said fluids for controlling the proportionate quantities delivered, means for periodically operating such devices, and means for changing the relative periods of such operations. 8

4. In a fluid mixing apparatus, the combination with a mixing receptacle, and means for compelling a plurality of fluids under pressure to be delivered separately thereinto, of a plurality of devices interrupting the flow of said fluids for controlling the proportionate quantities delivered, means for periodically operating said devices, and means for simultaneously changing the relative periods of such operations. 9

5. In a fluid mixing apparatus, the combination with a mixing receptacle, and means for compelling a plurality of fluids under constant pressure to be delivered separately thereinto, of a plurality of devices each interrupting the flow of a fluid to control the delivery thereof to said receptacle, a separate means for periodically operating each of said devices, and means for simultaneously changing the relative 100 periods of such operation. 10

6. In a fluid mixing apparatus, the combination with a mixing receptacle, and means for compelling a plurality of fluids under constant pressure to be delivered separately thereinto, of separate devices each interrupting the flow of one of said fluids for controlling proportionate quantities delivered to said mixing receptacle, separate means for periodically operating 11 each of said devices, and a common means for changing the relative operating periods of all of such devices to vary the proportions of fluids delivered. 12

7. In a fluid mixing apparatus, the combination with a mixing receptacle, means for compelling a plurality of fluids under constant pressure to be delivered separately thereinto, of a plurality of devices interrupting the flow of said fluids for controlling proportionate quantities delivered to said mixing receptacle, means for periodically operating such devices, and means for simultaneously changing the relative operating periods of all of said devices. 125 130

8. In a fluid mixing apparatus, the combination with a mixing receptacle, and means for compelling a plurality of fluids under constant pressure to be delivered separately thereinto, of a plurality of devices interrupting the flow of said fluids for controlling the proportionate quantities delivered to said receptacle, means for periodically operating such devices, and means for changing the relative operating periods of said devices.
9. In a fluid mixing apparatus, the combination of a common mixing receptacle, means for delivering a plurality of fluids separately thereinto, devices between said delivery means and said mixing receptacle for controlling proportionate quantities of fluids delivered to said receptacle, means for periodically operating such devices, and means for changing the relative periods of such operations.
10. In a fluid mixing apparatus, the combination with a mixing receptacle, and means for compelling a plurality of fluids under constant pressure to be delivered separately thereto, of a separate valve in advance of the mixing receptacle for interrupting and controlling the flow of each fluid into said receptacle, separate means for periodically opening said valves for a predetermined time to permit proportionate quantities of the fluids to pass into said mixing receptacle, and means for varying the relative length of time said valves remain open.
11. In a fluid mixing apparatus, the combination with a mixing receptacle, and means for causing a plurality of fluids to be delivered separately thereinto, of valves, each controlling the admission of fluid into said mixing receptacle, separate means for periodically and successively opening said valves for a predetermined time to permit proportionate quantities of the fluids to pass into said mixing receptacle, and means for varying the relative length of time the said valves remain open.
12. In a fluid mixing apparatus, the combination with a mixing receptacle, and means for causing a plurality of fluids to be delivered separately thereinto, of valves, each controlling the admission of fluid into said mixing receptacle, separate means for periodically and successively opening said admission valves for a predetermined time to permit proportionate quantities of the fluids to pass into said mixing receptacle and means for varying the relative length of time said valves remain open.
13. In a fluid mixing apparatus, the combination with a mixing receptacle, and means for causing a plurality of fluids to be delivered separately thereinto, of valves, each controlling the admission of fluid into said mixing receptacle, and a separate cam de-
- vice for periodically and successively opening each of said valves to permit proportionate quantities of fluids to pass into said mixing receptacle, and means for varying the relative length of time said valves remain open.
14. In a fluid mixing apparatus, the combination with a mixing receptacle, and means for causing a plurality of fluids to be delivered separately thereinto, of valves, each controlling the admission of fluid into said mixing receptacle, a sliding rod, a plurality of rocking members carried thereby each for opening one of said valves, and separate devices for periodically and successively operating said rocking members to open the valves and permit proportionate quantities of the fluids to flow therefrom to the mixing receptacle.
15. In a fluid mixing apparatus, the combination with a mixing receptacle, and means for causing a plurality of fluids to be delivered separately thereinto, of valves, each controlling the admission of fluid into said mixing receptacle, a plurality of rocking members each for opening one of said valves, separate devices for periodically and successively operating said rocking members to open the valves and permit proportionate quantities of the fluids to flow therethrough to the mixing receptacle, each of said separate devices comprising a plurality of means for holding the valves open varying lengths of time, and adjustable means carrying said rocking members for moving them in unison across said separate operating devices.
16. In a fluid mixing apparatus, the combination with a mixing receptacle, and means for causing a plurality of fluids to be delivered separately thereinto, of valves, each for controlling the admission of fluid into said mixing receptacle, a sliding rod, a plurality of rocking members carried thereby, each for opening one of said valves, and a separate moving cam surface for periodically and successively operating each of said rocking members to open the valves and permit proportionate quantities of the fluids to flow therethrough to the mixing receptacle.
17. In a fluid mixing apparatus, the combination with a mixing receptacle, and means for causing a plurality of fluids to be delivered separately thereinto, of valves, each controlling the admission of fluid into said mixing receptacle, and a separate revolute cam for periodically and successively causing each of said valves to open and permit proportionate quantities of the fluids to flow to the mixing receptacle, each of said revolute cams having a plurality of lifting surfaces of different lengths for varying the periods of time the several valves remain open.
18. In a fluid mixing apparatus, the combination with a mixing receptacle, and

means for causing a plurality of fluids to be delivered separately thereinto, of valves, each controlling the admission of fluid into said mixing receptacle, a sliding rod, a plurality of rocking members carried thereby, each for opening one of said valves, an extension on each rocking member parallel to said sliding rod to maintain connection between said members and the valve it operates as the rod is moved, and means for actuating said rocking members.

19. In a fluid mixing apparatus, the combination with a mixing receptacle, and means for causing a plurality of fluids to be delivered separately thereinto, of valves, each controlling the admission of fluid into said mixing receptacle, a sliding rod, a plurality of elbow levers fulcrumed on said rod, each for opening one of said valves, a right-angled finger on one end of each of said elbow levers extending parallel to said sliding rod and below the valve on which the stem of said valve bears, said fingers maintaining connection between the elbow levers and the valves as the sliding rod is moved, and means for actuating said elbow levers.

20. In a fluid mixing apparatus, the combination with a mixing receptacle, and means for causing a plurality of fluids to be delivered separately thereinto, of valves, each controlling the admission of fluid into said mixing receptacle, a sliding rod, a plurality of elbow levers fulcrumed on said rod, each for opening one of said valves, a right angled finger on one end of each of said elbow levers extending parallel to said sliding rod and below the valve on which the stem of said valve bears, said fingers maintaining connection between the elbow levers and the valves as the sliding rod is moved, and separate cams each having a plurality of lifting surfaces of different lengths for actuating the opposite ends of said elbow levers.

21. In a fluid mixing apparatus, the combination with a mixing receptacle, and means for compelling a plurality of fluids under pressure to be delivered separately thereinto, of a device for interrupting the

flow of each of said fluids and for controlling the quantity of the same delivered, means for operating said devices, and means for changing the period of operation of the devices.

22. In a fluid mixing apparatus, the combination with a mixing receptacle, and means for delivering a plurality of fluids under constant pressure to said receptacle, of a valve controlling each fluid, means for automatically and intermittently opening the valves, and adjustable means for adjusting the period of retaining the valves open.

23. In a fluid mixing apparatus, the combination with a mixing receptacle, and means for delivering fluids independently and under pressure to said receptacle, of a valve controlling each fluid, means for opening and closing said valves, and adjusting means for said first means adapted to change the period of opening and closing of each valve.

24. In a fluid mixing apparatus, the combination with a mixing receptacle, and means for delivering fluids independently under pressure to said receptacle, of a regulator for each fluid, operating means for the regulators to control the passage of fluid therethrough, and means for adjusting the operating means for varying the proportion of fluids passing through the regulators.

25. In a fluid mixing apparatus, the combination with a mixing receptacle, and means for compelling a plurality of fluids to be delivered separately and under pressure to said receptacle, of a valve for each fluid, opening and closing means for the valves whereby to control the passage of fluids therethrough, and adjusting means for said opening and closing means adapted to vary the amount of fluid passing through the valves.

In testimony whereof we have hereunto set our hands in presence of two subscribing witnesses.
